UNITED STATES PATENT OFFICE.

JOSEPH BURDA, OF CHICAGO, ILLINOIS.

GLASS-CUTTING DEVICE.

Application filed November 12, 1923. Serial No. 674,333.

My invention relates to improvements in glass cutting devices, and it consists in the combinations, constructions, and arrangements herein described and claimed.

5 The present invention is an improvement over my prior device set forth in Patent No. 1,282,375 of Oct. 22, 1918. In said prior patent, I disclosed a device by means of which glass could be conveniently measured and cut. The present invention relates to 10 improvements in the means by which the glass is held, the holding means being more easily applied and removed from the glass.

15 A further object of my invention is to provide an improved glass cutting device, in which the holding means is actuated by spring pressure, the springs forming part of the means for releasing and clamping the holding device in position.

20 Other objects and advantages will appear in the following specification, and the novel features of the invention will be particularly pointed out in the appended claims.

25 My invention is illustrated in the accompany drawings, forming part of this application, in which—

Figure 1 is a front elevation of one embodiment of the invention,

30 Figure 2 is an end view, and

Figure 3 is a detail plan view of a portion of the device.

35 In carrying out my invention, I provide a base 1, this being in the form of an elongated block, preferably made of wood. Carried by the block on its upper surface and extending rearwardly from the front edge thereof is a metal plate 2 which is designed to support the plate of glass to be cut, and which acts as a protecting member for the block 1, as well as affording a means which will easily permit the glass to slide therealong, without cutting into the block. At the rear edge of the block is disposed a strip 3 having a ruled surface for indicating one dimension of the plate of glass to be cut. It will be observed that the strip 3 is recessed so as to overlie the plate 2. The strip 3 may be secured to the block 1 by screws 4, or in any other suitable manner.

40 Arranged to slide along the side of the strip 3 is an abutment block or stop member 5. This, as will be observed from Figure 2, is provided with a U-shaped plate 6, which extends above the scale block 3 and downwardly on the rear side. An eccentric clamp 7 is provided for clamping the abutment

member 5 in any position along the scale. At the opposite end of the block is disposed an upright 8, having a vertical scale 9. Adjacent to this scale is a vertically extending clamping and holding member 10, which in the present instance is provided with a metal straight edge 11 on one side or edge thereof. The vertically extending block or plate 8 has secured at its top a metal plate 12 in the form of a hinge butt. This plate is slotted at 13 and is arranged to be held in adjusted position by means of set screws 14. It is pivotally connected at 15 by means of a link 16 with a spring plate 17, which is secured to the front face of the holding member 10 by screws 18. There is a pivotal connection at 19 between the plate 17 and the link 16.

45 Adjustably secured to the front face of the block 1, by means of set screws 20, is a spring metal plate 21 which is pivotally connected at 22 with a link 23, the latter being pivotally connected at 24 to a plate 25, which is secured to the bottom part of the holding member 10. A handle 26 is provided substantially midway between the upper and lower ends of the holding or clamping member 10.

50 From the foregoing description of the various parts of the device, the operation thereof may be readily understood. Normally the member 10 is in a position shown in dotted lines in Figure 2. When now it is desired to cut a plate of glass any given dimensions, the clamp 7 is loosened, and the edge of the stop member 5 facing the clamping device 10 is set at the distance on the scale indicating the dimension of the glass to be cut, this distance being measured 55 from a line 27 on the upright 8 to the right of the straight edge 11 in Figure 1, where the wheel of the glass cutter will be located as it follows the straight edge.

55 The abutment block is now clamped tight, and the plate of glass is inserted between the member 10 and the upright, and is pushed toward the abutment until it is arrested thereby. The handle 26 is then 60 grasped and swung upwardly and inwardly, and then downwardly into the position shown in dotted lines in Figure 2. This holds the glass firmly, no matter what the thickness is, since the spring members 17 and 21 will give to permit the glass of various 65 thicknesses to be held securely without any danger of breaking the glass. The arrange-

ment is such that the holding member is clamped, because it is dead-centered while in holding position, for it will be observed that in order for the holding device to be moved out of position, it will be necessary to raise it considerably. The glass cutter is now run along the straight edge, and in order to permit the cutter to go to the bottom of the glass, I provide the cut away portion 28 which permits the wheel of the glass cutter to go below the edge of the glass. The glass is instantly released by pulling upwardly, to swing the holding position back into its dotted line position. The plate may then be moved forwardly to the edge of the upright 8, and the glass may be snapped off by bending it along the edge in the usual manner.

It will be observed that the construction is such that the holding member 10 is moved toward and away from the upright 8, while substantially parallel to the upright, and that it is held firmly at the bottom in its closed position.

By adjusting the set screws 20 and 14, the upper or lower ends of the holding member may be shifted to adjust the vertical position of the straight edge.

It will be noted that the strip 3 is provided with a groove 28', and that the U-shaped plate 6 has an inwardly bent flange 29 arranged to slide in this groove. This prevents the displacement of the abutment block or stop member 5, so that even if the

device is inverted, the block will remain 35 in place, while it may be readily moved along the strip 3 at any time by releasing the handle 7, as already described.

I claim:

1. A glass cutting device comprising a 40 base, an upright secured thereto, a holding device for clamping the glass against the upright, said holding device being movable bodily toward and away from the upright, a link connected to the upper end of the 45 upright, a spring connecting said link with the upper end of the holding device, a spring secured to said base, and a link connected with said spring and secured to the lower end of said holding device. 50

2. A glass cutting device comprising a base of rectangular cross section, an upright carried by said base, a vertically disposed holding device for clamping the glass against the upright, said holding device being movable bodily toward and away from said upright, a spring secured at one end to said base and adapted to project slightly above the top thereof, a link connected with said spring at one end and with the lower part 60 of the holding device at the other, a link pivotally secured at the upper end of said upright, a spring securing said last named link with said holding device, and a handle carried by said holding device between the 65 upper and lower ends thereof. 55
